US0D1045530S

(12) **United States Design Patent** (10) **Patent No.:** **US D1,045,530 S**
(45) **Date of Patent:** **** Oct. 8, 2024**

(54) **CUPHOLDER**

(71) Applicant: **YETI Coolers, LLC**, Austin, TX (US)

(72) Inventors: **Liza Morris**, Austin, TX (US); **Max Burtner**, Austin, TX (US)

(73) Assignee: **YETI Coolers, LLC**, Austin, TX (US)

(**) Term: **15 Years**

(21) Appl. No.: **29/890,027**

(22) Filed: **Apr. 19, 2023**

Related U.S. Application Data

(63) Continuation of application No. 29/779,327, filed on Apr. 19, 2021, now Pat. No. Des. 988,094.

(51) **LOC (14) Cl.** **07-06**

(57) **CLAIM**

The ornamental design for a cupholder, as shown and described.

DESCRIPTION

FIG. 1 is a top, front perspective view of a cupholder showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the cupholder form no part of the claimed design.

1 Claim, 5 Drawing Sheets
